(57) **CLAIM**

The ornamental design for a mug grip pattern, as shown and described.

DESCRIPTION

FIG. 1 is a top, front perspective view of a mug grip pattern made in accordance with my new design having all but the design shown in phantom lines;

FIG. 2 is a front view of the embodiment of FIG. 1, with the back view being the mirror image of the front view having all but the design shown in phantom lines;

FIG. 3 is a left side view of the embodiment of FIG. 1, with the right side view being the mirror image of the front view having all but the design shown in phantom lines; and,

FIG. 4 is a bottom plan view thereof.

The broken lines in the drawings are for illustrative purposes only and form no part of the claimed design.

1 Claim, 4 Drawing Sheets
